By attorney.

UNITED STATES PATENT OFFICE.

CHARLES H. MEYER, OF SAN FRANCISCO, CALIFORNIA.

PIPE COVER.

Application filed May 29, 1922. Serial No. 564,425.

To all whom it may concern:

Be it known that I, CHARLES H. MEYER, a citizen of the United States, residing at San Francisco, in the county of San Francisco and State of California, have invented new and useful Improvements in Pipe Covers, of which the following is a specification.

This invention relates to a pipe cover and 10 has particular reference to a device adapted to be positioned over the bowl of a pipe for the purpose of rendering the said pipe sanitary.

A further object of this invention is to 15 provide a cover in the form of a sleeve made of elastic or a yielding material which is economical to manufacture and highly efficient in use.

Other objects and advantages will be apparent during the course of the following description.

In the accompanying drawings forming a part of this specification, and in which like numerals are employed to designate like 25 parts throughout the same,

Fig. 1 is a plan view of the device in a folded or collapsed position,

Fig. 2 is a perspective view of the device in an unfolded position, and

Fig. 3 is a side elevation of a pipe showing the application of my invention thereto.

Great annoyance has been experienced in the use of pipes due to the fact that they constantly cause the clothes or pockets of 35 the user to become foul by virtue of the burnt tobacco remaining in the pipe which causes a crust to accumulate therein.

To overcome this foregoing objection I have devised my improved cover which is 40 adapted to snugly engage the bowl of the pipe and thus prevent the foul odor from escaping.

In the accompanying drawings wherein for the purpose of illustration is shown a

preferred embodiment of my invention, the 45 numeral 5 designates a cap preferably made of asbestos and rubber although other material can be readily employed. To this cap I propose to secure by vulcanizing or other adhesive means, one extremity of a sleeve 6. 50 It will be observed that this sleeve terminates at its opposite extremity in an annular bead 7, which is provided for easily initiating and facilitating the rolling of the sleeve from its unfolded position shown in Figure 55 2 to the collapsed or folded position disclosed in Figure 1 and vice versa.

In practice, the cap 5 is positioned on the open end of the bowl and the sleeve is then unfolded until it assumes the position on the 60 bowl shown to advantage in Figure 3. When the cover is to be disengaged from the pipe bowl the user grasps in his fingers the bead 7 and rolls the same until the cover assumes the configuration disclosed in Figure 65 1 and the cover in a collapsed form is then transferred to the pocket of the smoker, where it will occupy but a minimum amount of space.

It is to be understood that the form of 70 my invention herewith shown and described is to be taken as a preferred example of the same, and that various changes in the shape, size and arrangement of parts may be resorted to without departing from the spirit 75 of the invention or the scope of the subjoined claim.

Having thus described my invention, I claim:

A pipe covering adapted to be positioned 80 on the bowl of a pipe, said cover being made of rubberized, foldable material and embodying in its construction a cap, a sleeve secured at one extremity to said cap and terminating at its opposite extremity in a bead. 85

In testimony whereof I affix my signature.

CHARLES H. MEYER.
